UNITED STATES PATENT OFFICE

JOSEPH F. KLEIN, OF PORT WASHINGTON, WISCONSIN

DESIGN FOR AN ASH TRAY

Application filed May 3, 1930. Serial No. 35,485. Term of patent 14 years.

To all whom it may concern:

Be it known that I, JOSEPH F. KLEIN, a citizen of the United States, of Port Washington, in the county of Ozaukee and the State of Wisconsin, have invented a new, original, and ornamental Design for an Ash Tray, of which the following is a specification, reference being had to the accompanying drawing, forming part thereof.

Figure 1 is a top plan view of an ash tray, showing my new design, the color lining in the drawing indicating black and red, respectively; and,

I claim:

The ornamental design for an ash tray, as shown and described.

In testimony that I claim the foregoing I have hereunto set my hand at Port Washington, in the county of Ozaukee and State of Wisconsin.

JOSEPH F. KLEIN.
